H. S. Wrightson.

Wrench.

No 73561

Patented Jan 21, 1868.

United States Patent Office.

HUGH S. WRIGHTSON, OF BALTIMORE, MARYLAND, ASSIGNOR TO M. M. WELBY AND C. H. SLICER, OF SAME PLACE.

Letters Patent No. 73,561, dated January 21, 1868.

IMPROVEMENT IN WRENCHES.

The Schedule referred to in these Letters Patent and making part of the same.

TO ALL WHOM IT MAY CONCERN:

Be it known that I, HUGH S. WRIGHTSON, of Baltimore city, in the county of Baltimore, in the State of Maryland, have invented a new and useful Improvement in the Construction of Wrenches.

This invention relates to a wrench which is a very cheap and simple construction, and which can be readily and easily adjusted to work of different kinds; and this wrench, owing to its simple construction, is not liable to be broken, or get out of order by use, a fault common to the adjustable-jaw wrenches now in common use; and I hereby declare the following to be a full, clear, and exact description of the construction and operation of my invention, the accompanying drawing being lettered to correspond with and making part of this specification; and in order that others may go on to manufacture and use my improvement, I will describe its construction and application, as follows. In the accompanying drawing—

Figure 1 represents a handle, and one stationary jaw of a common wrench, with two grooves cut across the entire width of one of its flat sides, just below the stationary jaw. These grooves are made one within the other, as shown by letters *a* and *b*, the larger groove *a* having teeth, like saw-teeth, the entire length of one of its sides. These grooves and teeth form a seat or socket, for the purpose of receiving an adjustable and movable jaw.

Figure 2 represents an adjustable and removable wrench-jaw, with tongue *d* and shoulder *e*, with teeth upon the lower edge of shoulder *e*, so that when this adjustable jaw is placed in the grooves or seats *a* and *b* of fig. 1, the parts fit and form a complete wrench, the adjustable jaw being secured to its place by means of a simple button or clasp, *E*, as seen in fig. 3. It may readily be seen that the tongue *d*, operating in the groove or seat *b*, performs an important office to this wrench. Whilst it adds very materially to the strength of the adjustable jaw, it also allows this jaw to open to a greater latitude than could be done without its aid, it becoming a shoulder or bearing for sustaining the strain, and at the same time holding the adjustable jaw's teeth to their adjusted place, with the simple aid of the button or clasp *E*.

Figure 3 is the wrench complete, with its adjustable jaw partly extended. The manner of extending or contracting the opening in the jaws of this wrench is different from that of other wrenches, and is accomplished by lifting out from its seat the adjustable jaw, and replacing it at the required distance from the stationary jaw, where it may be secured by means of the button *E*.

Figures 4, 5, and 6, are modifications of my invention.

I am aware that a single groove, partly across the flat side of a wrench, has been used for receiving the adjustable jaw, but not the two grooves, one within the other, as shown in my invention. I am also aware that teeth or ratchets are used for holding the jaw of a wrench to its adjusted place by the aid of screw or pawl, but the teeth, as used in my wrench, are neither located nor operated upon as in other wrenches. The teeth or ratchets, when arranged and located as in my improvement, make the operation of extending or contracting the opening in the jaws much more simple and effectual than what has heretofore been done, whilst at the same time they receive the strain of the jaw in such a manner as to add to their sustaining power when the wrench is being most severely tried, requiring neither screw nor other device, as is common to other wrenches to hold them by force to their work.

What I claim as my invention, and desire to secure by Letters Patent, is—

1. A wrench, with its adjustable jaw constructed and applied to its handle and stationary jaw, as described, when its ratchets or teeth are located as and operated in combination with groove *b* and tongue *d*, in the manner and for the purpose specified.
2. I also claim button *E*, in combination with groove *b* and tongue *d*, for holding the removable jaw to its seat, as herein described.

HUGH S. WRIGHTSON.

Witnesses:

SAM'L. G. SPICER,
THOMAS I. WELBY.
